(57) CLAIM

The ornamental design for a strength trainer, as shown and described.

DESCRIPTION

FIG. 1 is a front, right and top perspective view of a strength trainer, showing my new design;
FIG. 2 is a rear, left and bottom perspective view thereof;
FIG. 3 is a front view thereof;
FIG. 4 is a rear view thereof;
FIG. 5 is an enlarged left side view thereof;
FIG. 6 is an enlarged right side view thereof;
FIG. 7 is a top plan view thereof;
FIG. 8 is a bottom plan view thereof;
FIG. 9 is a perspective view with two grips of FIG. 1;
FIG. 10 is a perspective view with a crossbar of FIG. 1;
FIG. 11 is an enlarged view of portion of FIG. 1 thereof;
FIG. 12 is an enlarged view of portion of FIG. 1 thereof; and,
FIG. 13 is an enlarged view of portion of FIG. 2 thereof.
The broken lines shown in the drawings illustrate portions of the strength trainer that form no part of the claimed design.
